UNITED STATES PATENT OFFICE.

THEODORE B. LA RUE, OF SPOKANE, WASHINGTON.

SAFETY APPLIANCE FOR RAILWAY-CARS.

1,152,823.

Specification of Letters Patent.

Patented Sept. 7, 1915.

Application filed November 21, 1914. Serial No. 873,367.

To all whom it may concern:

Be it known that I, THEODORE B. LA RUE, a citizen of the United States, residing at Spokane, in the county of Spokane and State 5 of Washington, have invented certain new and useful Improvements in Safety Appliances for Railway-Cars, of which the following is a specification.

My invention relates to new and useful 10 improvements in safety appliances for street railway, interurban and steam cars of the type which are provided with automatic air brake systems.

The principal object of my invention is to 15 provide a safety device which may be used in cases of emergency by either the conductor, motorman, brakeman or any other member of the train crew and by the passengers as well, for quickly applying the air brakes to 20 bring the train or car to a full and almost immediate stop when a disastrous collision, derailment, or the like is about to occur.

It is a well known fact that many accidents could be avoided were it possible for 25 the passengers, who often times observe the tendency of a collision or derailment before the motorman, conductor or any other member of the train crew, to have within reach means whereby they could apply the emergency air brakes. For this purpose, therefore, I aim as a more specific object of my 30 invention to provide a safety appliance consisting essentially of a pair of cables, extending along the sides of the cars, which cables 35 are connected to the conductor's valve on the air line and are accompanied by a plurality of operating rods mounted transversely in the car, one being positioned beneath each seat thereof.

40 A further object of my invention is to mount the cables in metal tubes or pipes which are secured to the walls of the cars and are equipped with pulleys over which the cable rides.

45 An object of equal importance with the foregoing is to construct the appliance with such regard to proportion and arrangement of parts that it may be cheaply manufactured, will be durable and efficient in service, 50 and may be easily and quickly applied to any car, whether street, railway, interurban, or steam railway, without requiring any change in the construction of the car.

55 The above recited and other incidental objects of a similar nature, which will be hereinafter more specifically treated, are accom-

plished by such means as are illustrated in the accompanying drawings, described in the following specification, and then more particularly pointed out in the claims, which 60 are appended hereto and form a part of this application.

Referring now to the drawings, wherein there has been illustrated the preferred embodiment of this invention as it is reduced to 65 practice, and throughout the several views of which similar reference numerals designate corresponding parts, Figure 1 is a vertical section taken longitudinally through a car and showing the cable and associated 70 parts in position against one side wall of the car; Fig. 2 is an end view looking into one of the cable pipes and illustrating the manner in which the operating rod is freely attached to the cable; and Fig. 3 is a detail 75 perspective view showing the several parts of the apparatus in disassembled relation, but indicating the manner in which they are adapted to coact in forming an operative device.

80 In the accompanying drawings, my invention is shown as applied to a car 10, which is of conventional design and is equipped in the well-known manner with a plurality of longitudinally spaced transversely extending seats or chairs 11 arranged in rows on opposite sides of the car. A cable 12 is arranged on the side wall 13 of the car and is disposed for sliding movement through a plurality of metallic tubes or pipes 14 which 85 are secured, as by brackets 15, to the side wall 13 and extend longitudinally therealong a slight distance above the floor 16 of the car. If desired, a plurality of screw eyelets 90 may be substituted for the pipes 14. The 95 cable 12 is connected at its one terminal to the conductor's emergency valve which is provided in all standard cars having an automatic air brake system. The other terminal of the cable is, as shown in Fig. 1 at the 100 right hand side thereof, extended through the partition wall 17 which defines the toilet usually provided in interurban and steam railway cars. A handle 18, which may be of the type now in use, is provided for this terminal of the cable so that any occupant of the toilet may, upon observing an impending collision or derailment which does not appear to be noticed by the train crew, pull the cable 12 so as to open the conductor's valve 110 with the resultant application of the emergency brakes.

As has been hereinbefore explained, the purpose of my invention is to provide the cable 12 with a plurality of operating rods, there being one rod positioned beneath each chair 11 so that any occupant of the car may, upon observing an impending derailment, be able to operate the conductor's valve, upon short notice, for the purpose above explained. For this reason, therefore, the pipes 14 are approximately equal in length to the distance from center to center of the seats. Thus, it will be seen that at longitudinally spaced points a portion of the cable is exposed so that the operating rods, indicated at 19, may be connected to the cable.

The pipes 14, through which the cable 12 extends, are, as previously stated, secured to the side wall 13 by brackets 15. One of these brackets 15 is illustrated in detail in Fig. 3, and reference will, therefore, now be had to this figure. It will be seen that each of these members 15 includes a substantially U-shaped body member 20, the side portions or arms 21 and 22 of which are terminally bent at right angles and apertured, producing the vertically extending ears 23 which may be secured by bolts, rivets, screws or other suitable fastening devices to the side wall. Within the body member 20 and immediately adjacent the bight portion thereof is journaled, as on a pin 24, a pulley 25 over which the cable 12 plays in a manner to be hereafter more fully explained. The terminal of the pipe member 14 is clamped in the bracket 15 and in engagement with the bight portion thereof by means of a detachable holding or clamping plate 26. This plate 26 is transversely curved to conform to the face of the pipe and is terminally bent to produce the parallel apertured ears or wings 27. These wings 27 bear, when the plate is applied to the bracket, against the inner faces of the members 21 and 22 and are held in proper position thereagainst by the application of rivets or similar fastening devices through the apertures 28 which are formed in the members 21 and 22 and 50 are adapted to register with the apertures formed in the members 27.

From the foregoing description, it will be readily observed that the members 15 serve not only as a means for properly supporting the terminals of the several pipe members 14, but also as supporting members for the pulleys 25. The operating or drawing rods 19 are each formed from a single length of relatively stiff wire or 60 metal rod of light gage. These rods are each bent at their one terminal to form a hand ring or grip 29, and are bent at their other terminal to produce a substantially rectangular frame which includes the side members 30 and 31 and end members 32

and 33. It should be noted that the member 33 is free with respect to the side member 30. Within this frame is mounted for rotation on an axle 34 a pulley wheel 35. This pulley wheel 35 is adapted to receive the exposed portion of the cable 12 in the manner best shown in Figs. 2 and 3. It will be noted that the free end member 33 acts as a guard which will normally prevent the disengagement of the cable 12 from the pulley wheel 35. At the same time, it will be seen that the member 33 may be withdrawn from the member 30 such a distance as to permit the insertion of or withdrawal of the cable 12.

In attaching the operating rods 19 to the seats 11 so that they may slide in the base portions thereof, I employ for each seat a pair of bearing yokes or brackets, one of which is illustrated in detail in Fig. 3. This bracket or yoke includes a pair of diverging arms 36 and 37 which, together with a connecting portion 38, define a substantially V-shaped frame. The terminals of the members 36 and 37 are bent outwardly, as at 39 and 40, and are apertured so that they may be engaged against the bottom of the seat 11 and secured thereto by suitable fastening devices. The rod members 19 are arranged on the members 38 of the two brackets employed in connection with each seat and are secured thereon for sliding movement by means of half bearing plates, indicated at 41.

From the foregoing description, it will be apparent that each seat 11 of the car is equipped with a sliding rod which is freely connected to the cable 12. Thus, in case any one of the passengers observes the pendency of a derailment or the like which does not appear to be observed by the train crew, he may avert disaster by grasping the hand ring 29 and drawing the member 19 outwardly with the resultant shortening of the effective length of the cable 12 and the consequent opening of the conductor's valve in the air brake system.

In concluding the description of the invention, it may be well to explain that, while only one side of the car has been illustrated, it is my intention to provide for each side of the car, and thus for every seat therein, a rod 19 so that any occupant of the car may, upon observing a derailment, be enabled to manipulate the safety appliance. In this connection, it will be plain that it is necessary to equip both sides of the car with a cable 12.

Under some conditions, it may be deemed expedient to omit the pulley 35 and to attach the member 19 to the cable by merely engaging the frame-shaped terminal of the rod with the cable. I, therefore, desire to emphasize the fact that such a modification is entirely within the spirit of my invention.

In reduction to practice, it has been found that the form of this invention illustrated in the drawings, and referred to in the above description as the preferred embodiment, is the most efficient and practical; yet realizing that the conditions concurrent with the adoption of this device will necessarily vary, it is desirable to emphasize the fact that various minor changes in details of construction, proportion and arrangement of parts may be resorted to, when required, without sacrificing any of the advantages of this invention, as defined in the appended claims.

Having thus described the invention, what is claimed as new is:—

1. The combination with a car having an automatic air brake system, of an emergency controlling apparatus for the system, said apparatus including a plurality of tubes, each of a length slightly less than the distance from center to center of the car seats, a cable extending through the tubes and connected to the conductor's valve of the air brake system, and means slidable transversely beneath the seats of the car and connected to the exposed portions of the cable whereby the effective length of the same may be lessened with the consequent opening of the conductor's valve.
2. The combination with a car having an automatic air brake system, of an emergency controlling apparatus including a cable attached to the conductor's valve, a plurality of tube members arranged with their terminals in spaced relation to the terminals of the adjacent tube members, brackets removably securing the tubes to the side walls of the car, said tubes receiving the cable member, rods slidable transversely of the car and secured beneath the seats thereof, frame

members formed on the terminals of the rods, and pulleys journaled in the frames and engaged with the adjacent exposed portions of the cable which lie between the adjacent terminals of each pair of tube members.

3. The combination with a car having an automatic air brake system, of an emergency controlling apparatus, said apparatus including a cable extending longitudinally along the sides of the car and connected to the conductor's valve of the air brake system, a plurality of tubes through which the cable extends, there being a portion of the cable exposed between the adjacent terminals of the tubes, and a plurality of rods mounted for transverse sliding movement in the car, said rods being freely connected at their terminals to the exposed portions of the cable, said rods being adapted upon movement away from the side of the car to shorten the effective length of the cable, whereby the conductor's valve may be opened.

4. An emergency controlling apparatus adapted for attachment to a car having an automatic air-brake system, said apparatus including a cable connected to the conductor's valve of said system, an operating rod freely engaging the cable, and brackets slidably connecting the rod to a seat of the car, whereby the effective length of the cable may be shortened upon the actuation of said rod to thereby open the conductor's valve.

In testimony whereof I affix my signature in presence of two witnesses.
